HIS ATTORNEY

UNITED STATES PATENT OFFICE.

CHARLES H. SHEPARD, OF JAMAICA, NEW YORK, ASSIGNOR TO REMINGTON TYPE-WRITER COMPANY, OF ILLION, NEW YORK, A CORPORATION OF NEW YORK.

TYPE-WRITING MACHINE.

1,115,871.

Specification of Letters Patent.

Patented Nov. 3, 1914.

Application filed January 29, 1914; Serial No. 815,129.

To all whom it may concern:

Be it known that I, CHARLES H. SHEPARD, citizen of the United States, and resident of Jamaica, in the county of Queens and State 5 of New York, have invented certain new and useful Improvements in Type-Writing Machines, of which the following is a specification.

My invention relates to typewriting machines and more particularly to carriage escapement mechanism for such machines.

One of the objects of my invention, generally stated, is to provide an escapement which is comparatively simple in construction and which is rapid, efficient and reliable in use.

A further object of my invention is to provide an improved escapement mechanism which may be regulated to feed "ordinary" 20 or "reverse" as may be desired.

Another object of my invention, generally stated, is to provide improved cushioning means for absorbing the shock incidental to the "let-off" or "drop" of the carriage, 25 thereby producing an easy acting escapement free from the usual shock or jar and one in which the noise ordinarily produced by the feed of the carriage is greatly reduced or entirely eliminated.

To the above and other ends which will hereinafter appear, my invention consists of 30 the features of construction, arrangements of parts and combinations of devices set forth in the following description and particularly 35 pointed out in the appended claims.

In the accompanying drawings wherein like reference characters indicate corresponding parts in the various views, Figure 1 is a detail fragmentary full sized rear 40 elevation of the escapement mechanism as the parts appear in the normal position when arranged to operate for "ordinary" feed. Fig. 2 is a fragmentary full sized elevation with parts broken and sectioned away 45 and showing a sufficient number of parts of a typewriting machine to illustrate my invention in its embodiment therein. Fig. 3 is a view which corresponds substantially to Fig. 2 except that the parts are shown as 50 they are normally disposed when arranged for "reverse" feed. Fig. 4 is a detail fragmentary sectional view showing a modified form of cushioning means. Fig. 5 is a dia-

grammatic rear view showing parts of the escapement mechanism as they appear when 55 arranged for "ordinary" feed and indicating in dotted lines the disposition of the engaging portions of the dogs as they appear just before the release of the wheel by the normally engaged dog. Fig. 6 is a diagrammatic view showing the parts of the escapement as they appear when arranged for "reverse" feed and showing the engaging portions of dogs in dotted lines as they appear just before the release of the wheel by 65 the normally engaged dog.

I have shown my invention in the present instance embodied in a No. 10 Remington machine. It should be understood, however, that the invention may be embodied in various 70 styles of typewriting machines and that various changes may be made accordingly.

The frame of the machine comprises a top plate 1 which supports fixed guide rails 2 oppositely grooved to receive anti-friction 75 balls or rollers 3, the latter also being received in oppositely grooved guide ways 4 in the front and rear rails which constitute a portion of the carriage 5. A cylindrical platen 6 is carried by the carriage for movement therewith from side to side of the machine over the top plate 1. The carriage is power driven, being moved under control of its escapement mechanism by a spring drum 7 which has one end of a band 8 connected thereto at 9. The opposite end of the band is connected to a bracket arm 10 which is secured to the carriage by screws 11. Ears 12 are secured to the carriage, and pivoted to the ears at 13 are rearwardly extending 90 arms 14 to which a feed rack 15 is connected. This rack engages a feed pinion 16 fixed to the forward end of a shaft 17 which turns in a bearing 18 secured to the top plate of the machine. To the rear end of the shaft 17 is 95 fixed an escapement rack or wheel 19. Thus the hub 20 of the escapement wheel is tapped to receive a screw 21 which bears at its inner end against a flattened portion on the rear end portion of the shaft 17, to fixedly 100 connect the escapement wheel to the shaft. A bracket plate 22 is fixed by screws 23 to a second bracket plate 24, which latter in turn is secured to the top plate of the machine and constitutes a support for the 105 spring drum.

From an inspection of Figs. 1 and 2 it will be seen that a shouldered pivot screw 25 is received at its threaded end in a tapped opening in a supporting plate 26 and turns 5 freely at its shouldered portion in a bearing opening in the bracket 22, thus forming a pivotal bearing for said supporting plate 26. The supporting plate 26 is provided with a laterally projecting extension or lug 27 which constitutes a stop or contact. The stop 27 is adapted to co-act with a second contact device 28, which is preferably made of felt or some such suitable material, and is carried at the upper end of a set screw 29. 10 This screw is received in a tapped opening in a laterally projecting arm or lug 30 which extends from the supporting plate 22. The screw 29, sheathed at its end as at 28, constitutes an adjustable stop with which the 15 stop 27 co-acts to limit the pivotal movement of the supporting plate 26 in one direction. The plate 26 is slotted at 31 for the reception of one end of a C-spring 32, the opposite end of said spring being secured by a screw 33 to the fixed bracket plate 22. The power of the spring 32 tends to turn the supporting plate 26 on its pivot 25 so as to move the stop 27 out of contact with its co-operative stop 29. However, the 20 force of the spring drum, exerted through the escapement wheel and through the feed dogs, is sufficient to overcome the power of the spring 32 and turn the plate 26 on its pivot to bring the stop 27 into contact with the sheathed end of the stop 29, as will hereinafter more clearly appear.

There are two feed dogs 34 and 35. The dog 34 has a rearwardly engaging portion 36 which projects laterally from the plane 40 of the body portion of the dog, said engaging portion being adapted to move into and out of engagement with the escapement wheel in the plane of the latter. The dog 34 is pivoted at 37 to an arm, lever or carrier 38, pivoted on a shouldered pivot screw 39 to the movable support 26. The tail of the feed dog 34 carries a laterally projecting abutment 40 which overlaps the supporting arm or carrier 38 for the feed dog and limits 45 the relative movement between the dog and carrier in one direction. A spring 41 is fixed at one end to the supporting arm or carrier 38 and bears at its free end against the body portion of the dog 34 above the 50 pivot thereof in order to normally maintain the dog on its carrier in the position shown in Fig. 1. It will be understood, however, that when the parts are disposed as indicated in Fig. 3, and the carriage is moved 55 from left to right to begin a new line of writing, the escapement wheel will receive a reverse rotation in the direction of the arrow in Fig. 3. During such movement of the escapement wheel the dog 34 will be 60 turned on its pivot 37 against the pressure 65

of the spring 41 to prevent the dog from obstructing the backward rotation of the escapement wheel. The dog 35 is provided with a forwardly extending engaging portion 42 which extends laterally from the body portion of the dog and moves into and out of engagement with the escapement wheel in the plane thereof. This feed dog is pivoted at 43 to an arm or carrier 44 pivoted on a shouldered pivot screw 45 to the 70 plate-like support 26. A spring 46 is fixed at one end to the carrier 44, and bears at its free end portion against the tail of the feed dog 35 below the pivot thereof. When the parts are normally disposed as indicated in Fig. 1 a backward rotation of the escapement wheel is effective to turn the feed dog 35 on its pivot 43 so as not to obstruct the escapement wheel in its reverse rotation. In the normal position of the parts, shown 80 in Fig. 1, the tail of the feed dog 35 bears against the body portion of the arm or carrier 44 to limit the relative movement between the feed dog 35 and its carrier in one direction and the spring 46 normally maintains the feed dog 35 in such position. The carrier 44 has a slot 47 therein, the center of the arc forming said slot corresponding to the pivot 45 of the carrier. A pin or post 48 (see Fig. 2) extends laterally from the 85 plate-like support 26 and is tapped at its outer end to receive a shouldered screw 49. This screw passes through the slot, the head of the screw overlapping the slot to guide the carrier 44 and limit its pivotal movements in opposite directions. The arm or carrier 38 is extended beyond its pivot 39 to form an arm 50 which constitutes one element of a toggle. The upper end of this arm is pivoted, at 51, to a link 52 which constitutes the other element of the toggle. The upper end of this link is pivoted, at 53, to the carrier 44 intermediate the ends of the latter. It will thus be understood that the carriers 38 and 44 of the dogs are connected together in such a manner that a movement of one of the dogs out of engagement with the escapement wheel is effective to cause the other dog to move into engagement therewith.

I have provided means by which either feed dog may be made the normally engaged dog, and by which either "ordinary" or "reverse" feed of the carriage may be provided, as desired. In the present instance I 105 have provided means by which an actuating member for the escapement may be connected to the carrier 44, when the parts will be normally positioned as represented in Fig. 1 for "ordinary" feed, or said member 110 may be connected to the carrier 38, so that the parts may be normally disposed in the positions represented in Fig. 3 for "reverse" feed. This actuating member in the 115 present instance comprises a link 54 which 120

may be actuated by the key controlled universal bar in the usual manner, a downward pull on the link being effected at each actuation of a printing key. Any suitable means may be employed for readily effecting a connection between this link and either of the dog carriers 38 and 44. In the present instance I have provided a laterally projecting pin 55 at the upper end of the link, said pin having a head 56, as shown in Fig. 2. The pin is adapted to be received in an open-mouth bearing opening 57 formed in the carrier 44. The mouth of this bearing opening is closed by a spring 58, secured at 59 on the edge of the carrier 44. By deflecting the free end of the spring to the left, as the parts appear in Fig. 3, the pin 55 may be displaced from the bearing opening 57, so as to disconnect the link from the carrier 44. The carrier 38 is also provided with an open-mouth bearing opening corresponding to the opening 57 and in which the pin 55 may be seated to connect the link 54 with the carrier 38. A spring 60 is formed as an extension of the spring 41, and extends at its free end over the open mouth of the bearing opening in the member 38, as indicated in dotted lines in Fig. 3. The combined spring 41 and 60 is connected to the upper edge of the carrier 38, as indicated at 61. It will be understood that the spring devices 58 and 60 enable the link to be readily disconnected from one dog carrier and connected with the other.

35 When the link 54 is connected to the dog carrier 44, as shown in Fig. 1, the feed dog 35 will normally engage the escapement wheel, and the parts will be set or arranged for "ordinary" feed. On the other hand, 40 when the link 54 is connected to the carrier 38, as shown in Fig. 3, the feed dog 34 will be the normally engaged dog and the parts will be set or arranged for "reverse" feed, all as will hereinafter more clearly appear.

45 A contractile spring 62 is connected at one end to the actuating device or link 54, as indicated at 63, the opposite end of said spring being connected to a swivel 64. This swivel is carried by a set screw 65 which is received in a tapped opening in a post or pin 66 which projects rearwardly from the fixed supporting bracket 22. The tension of the spring 62 may be varied by adjusting the screw 65, thus enabling a variation in the power of the spring 62 to be exerted on the feed dogs to return them to normal position, and to assist in some instances to resist the advance of the escapement wheel.

50 When the parts are set or arranged for "ordinary" feed as indicated in Fig. 1, the operation of the printing key is effective to pull down the link 54 as the type bar approaches the printing position. The effect 55 of this movement of the link is to with-

draw the normally engaged feed dog 35 from, say, the tooth *b* of the wheel, and to simultaneously move the normally disengaged dog 34 toward the tooth *b* of the escapement wheel. From an inspection of Fig. 5 it will be understood that when the engaging portion 42 of the feed dog 35 moves from the full line to the dotted line position shown in this figure, the engaging portion 36 of the feed dog 34 is moved from the full line 70 to the dotted line position in said figure. From a comparison of the positions of the dogs in Fig. 5 it will be seen that the engaging portion 36 of the normally disengaged dog 34 is interposed in the path of an advancing tooth of the escapement wheel before the engaging portion 42 of the normally engaged dog 35 is disengaged from the wheel, so that there is an assurance of the proper action and no liability of the escapement skipping. As the feed dog 35 continues its movement away from the escapement wheel the dog 34 will continue to advance toward the working face of the disengaged tooth *b* of the wheel to arrest the 80 latter before it has had an opportunity to advance under the action of the spring drum. The dogs at this time will be in positions corresponding substantially to the 85 position of the dogs shown in Fig. 3. 90

When pressure is released on the depressed finger key the link 54 will move upwardly under the action of the returning spring 62, thus moving the dog 35 upwardly into the path of the next advancing tooth *c* of the escapement wheel, and moving the dog 34 from the position corresponding to that shown in Fig. 3 to the position of said dog represented in Fig. 1. It will be understood that during this return movement of the dogs to normal position the tooth *b* of the escapement wheel will follow up the dog 34 in its retrograded movement until the wheel is finally arrested by the next tooth *c* of the wheel co-acting 100 with the dog 35. It will be understood that in the movements of the feed dog 35 into and out of engagement with the escapement wheel, the engaging portion 42 of this dog will describe a path which is substantially 105 radial of the escapement wheel as indicated in Fig. 6. On the other hand the movement of the engaging portion 36 of the dog 34 into and out of engagement with the escapement wheel describes a path which is at 110 substantially right angles to the movement of the engaging portion of the dog 35, and in such movement the part 36 advances toward and recedes from the working face of 115 an oncoming tooth of the escapement wheel. 120

When the parts are set as represented in Fig. 3 for "reverse" feed the downward movement of the actuating link is effective to withdraw the normally engaged dog 34 from the escapement wheel. Referring par- 125 130

ticularly to Fig. 6 the dot and dash line *a* therein shown may be presumed to represent the working face of the engaged tooth of the escapement wheel. As the link 54 moves down from the position shown in Fig. 3, the engaging portion 36 of the feed dog 34 will move from the full to the dotted line position represented in Fig. 6, and throughout this movement an advance of the escapement wheel will be effected. From an inspection of this figure it will be seen that most of the letter feed advance of the carriage has taken place (an advance of the wheel from *a* to *b*) before the dog 35 is disengaged from the wheel, and before such disengagement has been effected the engaging portion 42 of the feed dog 35 has been moved from the full to the dotted line position represented in this figure so as to be interposed in the path of the next advancing tooth *c* of the escapement wheel. When the dog 34 disengages the wheel a further advance movement thereof will be effected until it is arrested by the dog 35. This advance of the escapement wheel is effected during the down stroke of the key and during a movement of the type bar to the printing position. At the completion of this down stroke the dogs will be positioned substantially as represented in Fig. 1, it being understood that a letter space advance of the carriage has taken place at this time. When pressure on the depressed finger key is released the dog 34 will again advance to the position shown in Fig. 3, attaining such position before the escapement wheel has had an opportunity to advance.

The pressure of the escapement wheel exerted on the feed dogs is resisted by and is finally exerted against the spring 32, and the carriage spring pressure is sufficient to overcome the power of the spring 32 as hereinbefore pointed out. When both of the feed dogs are free from engagement with the escapement wheel the pivoted support 26 is turned on its pivot so as to carry the stop 27 away from the upper end of the stop 29. When the "let-off" or "drop" of the carriage is effected, it results in a shock or pressure being exerted by the escapement wheel on either of the feed dogs. This pressure overcomes the power of the spring 32 and the pivoted support 26 is turned on its pivot until the support is arrested by the stop 29, as indicated at Fig. 1. The construction and arrangement of the parts thus described, and the power of the spring 32 are such as to cushion and absorb the shock incidental to the "let-off" or "drop" of the carriage, or to the action of the escapement wheel on the dogs, thus avoiding the noise ordinarily incidental to the feed of the carriage. The above result is attained whether the feed dog 34 or the dog 35 be made the normally engaged dog or, in other words, whether

the escapement be set or arranged for "ordinary" or "reverse" feed. The resistance offered to the advance of the carriage in all cases is effected through cushioning means which absorbs the shock and resists or prevents a blow from being imparted in a noisy manner to the parts. This results in an escapement which is easy in its action and greatly reduces or entirely eliminates the noise ordinarily incidental to an operation of the escapement.

In Fig. 4 I have shown a modified form of cushioning device coöperating with the pivoted support 26. In this modified form of construction a rod 67 is pivoted at its upper end, as at 68, to the pivoted support 26. The lower end of this rod carries a piston 69 which works in a cylinder 70. A spring 71 is interposed between the closed bottom of the cylinder and the head of the piston to return the piston head and the parts connected therewith to normal position. The cylinder 70 is fixed on a bracket 72 which is secured by screws 73 to the fixed supporting bracket 72. The construction thus described constitutes a dash pot connected to the pivotal support 26 to resist the movement of the latter under the action of the escapement wheel on the feed dogs and to absorb the shock incidental to the action of the escapement wheel on the feed dogs.

From the foregoing description it will be understood that the support 26 is yieldingly mounted; that resilient means are provided which tend to resist the movement of the support 26 under the action of the escapement rack (circular), or wheel 19 on the feed dogs; that the support 26 is movable only in a plane at right angles to the axis of the escapement wheel; that when the link 54 is connected to the carrier 44 the mechanism is set to operate indefinitely as an "ordinary" escapement, whereas when the link 54 is connected to the carrier 38 the mechanism is set to operate indefinitely as a "reverse" escapement; that the feed dogs, carriers and intermediate connections constitute an escapement device which is in the nature of an anchor escapement device having pallets or dogs positively connected by jointed connections to move in unison and by which the movement of one pallet or dog into the path of an oncoming tooth of the escapement wheel will be effected before the other pallet or dog disengages the wheel.

While I have described with considerable particularity one form of construction embodying my invention it will be understood that various changes may be made without departing from the spirit and scope thereof.

What I claim as new and desire to secure by Letters Patent, is:—

1. In a typewriting machine, the combination of a power driven carriage; and escapement mechanism therefor, said escape-

ment mechanism comprising an escapement rack, a feed dog the engaging portion of which is movable in the plane of the rack into and out of engagement therewith, and a yielding support on which said dog is mounted for movement independently of said support into and out of engagement with said feed rack,

2. In a typewriting machine, the combination of a power driven carriage; and escapement mechanism therefor, said escapement mechanism comprising an escapement rack, a feed dog the engaging portion of which is movable in the plane of the rack into and out of engagement therewith, means for controlling such movements of the feed dog, and a yieldingly supported carrier separate from the feed dog and its controlling means and on which the feed dog is movably mounted.

3. In a typewriting machine, the combination of a power driven carriage; and escapement mechanism therefor, said escapement mechanism comprising an escapement rack, a feed dog the engaging portion of which is movable in the plane of the rack into and out of engagement therewith, a support mounted for a limited movement and on which the feed dog is independently movable into and out of engagement with said feed rack, and resilient means which tends to resist a movement of said support under the action of the rack on said feed dog.

4. In a typewriting machine, the combination of a power driven carriage; and escapement mechanism therefor, said escapement mechanism comprising an escapement rack, a feed dog the engaging portion of which is movable in the plane of the rack into and out of engagement therewith, a support pivoted to swing in a plane coincident or parallel with the plane of the feed rack and on which the feed dog is independently movable into and out of engagement with the feed rack, and shock absorbing means which tend to resist a pivotal movement of said support under the action of the rack on said feed dog.

5. In a typewriting machine, the combination of a power driven carriage; an escapement mechanism therefor including means for affording either "ordinary" or "reverse" feed as may be desired, and also including cushioning means for absorbing the shock incidental to the "let-off" or "drop" of the carriage whether the carriage be feeding under "ordinary" or "reverse" feed, and final stopping means for said escapement.

6. In a typewriting machine, the combination of a power driven carriage, an escapement wheel, escapement dogs therefor, dog carriers, means for actuating said dog carriers, final stopping or limiting means

for said dog carriers, and intermediate cushioning means for said wheel and dogs.

7. In a typewriting machine, the combination of a power driven carriage; and escapement mechanism therefor comprising feed dogs, a separate carrier for each feed dog, operative connections between said carriers, an actuating device, and means for connecting said actuating device to one or another of said carriers, the escapement mechanism operating for "reverse" feed when said actuating device is connected to one carrier and operating for "ordinary" feed when the actuating device is connected to the other carrier.

8. In a typewriting machine, the combination of an escapement wheel, escapement, dogs, dog carriers, a cushioned support for said dog carriers, a final stop for said support, and means for actuating said dogs.

9. In a typewriting machine, the combination of a power driven carriage; and escapement mechanism therefor comprising feed dogs, a separate carrier for each feed dog, operative connections between said carriers, an actuating device, means for connecting said actuating device to one or another of said carriers, the escapement mechanism operating for "reverse" feed when said actuating device is connected to one carrier, and operating for "ordinary" feed when the actuating device is connected to the other carrier, and cushioning means for absorbing the shock incidental to the "drop" or "let-off" of the carriage whether the carriage be feeding under "ordinary" or "reverse" feed.

10. In a typewriting machine, the combination of a power driven carriage; and escapement mechanism therefor comprising an escapement wheel, co-operative relatively movable feed dogs, a support, an arm pivoted intermediate its ends to said support and constituting a carrier for one of said feed dogs, a second arm pivoted to said support and constituting a carrier for the other of said dogs, a link connecting said arms, and means for actuating said arms.

11. In a typewriting machine, the combination of a power driven carriage; and escapement mechanism therefor comprising an escapement wheel, co-operative relatively movable feed dogs, a support, an arm pivoted intermediate its ends to said support and constituting a carrier for one of said feed dogs, a second arm pivoted to said support at one end and constituting a carrier for the other of said dogs, a link connected at one end to one end of said first mentioned arms and at its other end to the other arm and intermediate the ends of the latter, and means for actuating said arms.

12. In a typewriting machine, the combination of a power driven carriage; and escapement mechanism therefor comprising an escapement wheel, co-operative relatively

movable feed dogs, a support, an arm pivoted to said support and constituting a carrier for one of said feed dogs, a second arm pivoted to said support and constituting a carrier for the other of said dogs, a link connecting said arms, means for actuating said arms, and cushioning means for said support.

13. In a typewriting machine, the combination of a power driven carriage; and escapement mechanism therefor comprising an escapement wheel, co-operative relatively movable feed dogs, a support, an arm pivoted intermediate its ends to said support and constituting a carrier for one of said feed dogs, a second arm pivoted to said support at one end and constituting a carrier for the other of said dogs, a link connected at one end to one end of said first mentioned arm and at its other end to the other arm and intermediate the ends of the latter, means for actuating said arms, and cushioning means for said support.

14. In a typewriting machine, the combination of a power driven carriage; and escapement mechanism therefor comprising an escapement wheel, two feed dogs which co-act therewith, the engaging portion of one of said feed dogs moving into and out of engagement with the wheel in a line which is substantially radial of the wheel, an engaging portion of the other dog moving toward and away from the working face of the oncoming tooth of the escapement wheel as said dog engages and disengages the wheel, and means whereby either dog may be made the normally engaged dog and the escapement mechanism be set to feed either "ordinary" or "reverse" as may be desired.

15. In a typewriting machine, the combination of a power driven carriage; and escapement mechanism therefor comprising an escapement wheel, two feed dogs which co-act therewith, the engaging portion of one of said feed dogs moving into and out of engagement with the wheel in a line which is substantially radial of the wheel, the engaging portion of the other dog moving toward and away from the working face of the oncoming tooth of the escapement wheel as said dog engages and disengages the wheel, an actuating device, and means for variably connecting said actuating device relatively to said dogs and thus set the escapement mechanism to feed either "ordinary" or "reverse" as may be desired.

16. In a typewriting machine, the combination of a power driven carriage; and escapement mechanism therefor comprising an escapement wheel, two feed dogs which co-act therewith, the engaging portion of one of said feed dogs moving into and out of engagement with the wheel in a line

which is substantial radial of the wheel, 65 the engaging portion of the other dog moving toward and away from the working face of an oncoming tooth of the escapement wheel as said dog engages and disengages the wheel, means whereby either dog may be 70 made the normally engaged dog and the escapement mechanism be set to feed either "ordinary" or "reverse" as may be desired, and cushioning means for absorbing the shock incidental to the "drop" or "let-off" of 75 the carriage whether the carriage be feeding under "ordinary" or "reverse" feed.

17. In a typewriting machine, the combination of a power driven carriage; and escapement mechanism therefor comprising 80 an escapement wheel, two feed dogs which co-act therewith, the engaging portion of one of said feed dogs moving into and out of engagement with the wheel in a line which is substantially radial of the wheel, 85 the engaging portion of the other dog moving toward and away from the working face of the oncoming tooth of the escapement wheel as said dog engages and disengages the wheel, an actuating device, means for variably connecting 90 said actuating device relatively to said dogs and thus set the escapement mechanism to feed either "ordinary" or "reverse" as may be desired, and cushioning means for absorbing 95 the shock incidental to the "drop" or "let-off" of the carriage irrespective of which of said dogs is made the normally engaged dog.

18. In a typewriting machine, the combination of a power driven carriage; and escapement mechanism therefor comprising an escapement wheel, a support movable only in a single plane at right angles to the axis of the escapement wheel, feed dogs carried by said support and movable thereon so that the engaging portions of said dogs move in the plane of the escapement wheel into and out of engagement therewith, and cushioning means which tend to resist the 110 movement of said support.

19. In a typewriting machine, the combination of a power driven carriage; and escapement mechanism therefor comprising an escapement wheel, a support movable 115 only in a single plane at right angles to the axis of the escapement wheel, feed dogs carried by said support and movable thereon so that the engaging portions of said dogs move in the plane of the escapement wheel into and out of engagement therewith, cushioning means for said support, operating means for said dogs, and means for varying the operative connection of said operating 120 means relatively to said dogs to set the escapement mechanism to feed "ordinary" or "reverse" as may be desired.

20. In a typewriting machine, the combi-

nation of a power driven carriage; and escapement mechanism therefor comprising an escapement wheel, feed dogs, toggle connections between said feed dogs for moving 5 one of the dogs into engagement with said wheel when the other dog is moved out of engagement therewith, and means for actuating said toggle.

21. In a typewriting machine, the combination of a power driven carriage; and escapement mechanism therefor comprising an escapement wheel, feed dogs, toggle connections between said feed dogs for moving one of the dogs into engagement with said 15 wheel when the other dog is moved out of engagement therewith, and means for actuating said toggle, the movement of one dog into the path of an oncoming tooth of the escapement wheel being effected before 20 the other dog is disengaged from the wheel.

22. In a typewriting machine, the combination of a power driven carriage; and escapement mechanism therefor comprising an escapement wheel, feed dogs, toggle connections between said feed dogs for moving 25 one of the dogs into engagement with said wheel when the other dog is moved out of engagement therewith, means for actuating said toggle, and means by which either dog 30 may be made the normally engaged dog.

23. In a typewriting machine, the combination of a power driven carriage; and escapement mechanism therefor comprising an escapement wheel, feed dogs, toggle connections between said feed dogs for moving 35 one of the dogs into engagement with said wheel when the other dog is moved out of engagement therewith, means for actuating said toggle, and means by which a change 40 in the point of connection between said actuating means and toggle may be effected to afford "ordinary" or "reverse" feed as may be desired.

24. In a typewriting machine, the combination of a power driven carriage; and escapement mechanism therefor comprising an escapement wheel, feed dogs, toggle connections between said feed dogs for moving 45 one of the dogs into engagement with said wheel when the other dog is moved out of engagement therewith, means for actuating said toggle, and means by which either dog 50 may be made the normally engaged dog, the movement of one dog into the path of an oncoming tooth of the escapement wheel being effected before the other dog is disengaged from the wheel irrespective of which dog is the normally engaged dog.

25. In a typewriting machine, the combination of a power driven carriage; and escapement mechanism therefor comprising an escapement wheel, feed dogs, toggle connections between said feed dogs for moving 55 one of the dogs into engagement with

said wheel when the other dog is moved 65 out of engagement therewith, means for actuating said toggle, a movable support for said toggle and feed dogs, and cushioning means which tend to resist the movement of said support under the action of the 70 power of the carriage applied through said feed dogs.

26. In a typewriting machine, the combination of a power driven carriage; and escapement mechanism therefor comprising an escapement wheel, feed dogs, toggle connections between said feed dogs for moving one of the dogs into engagement with said wheel when the other dog is moved out of engagement therewith, means for actuating 80 said toggle, the movement of one dog into the path of an oncoming tooth of the escapement wheel being effected before the other dog is disengaged from the wheel, a movable support for said toggle and feed 85 dogs, and cushioning means which tend to resist the movement of said support under the action of the power of the carriage applied through said feed dogs.

27. In a typewriting machine, the combination of a power driven carriage; and escapement mechanism therefor comprising an escapement wheel, feed dogs, toggle connections between said feed dogs for moving one of the dogs into engagement with said 95 wheel when the other dog is moved out of engagement therewith, means for actuating said toggle, the movement of one dog into the path of an oncoming tooth of the escapement wheel being effected before the 100 other dog is disengaged from the wheel, a movable support for said toggle and feed dogs, and cushioning means which tend to resist the movement of said support under the action of the power of the carriage 105 applied through said feed dogs irrespective of which dog is the normally engaged dog.

28. In a typewriting machine, the combination of a power driven carriage; and escapement mechanism therefor comprising an escapement wheel, feed dogs, toggle connections between said feed dogs for moving one of the dogs into engagement with said wheel when the other dog is moved out of engagement therewith, means for actuating 115 said toggle, means by which a change in the point of connection between said actuating means and toggle may be effected to afford "ordinary" or "reverse" feed as may be desired, a movable support for said toggle and 120 feed dogs, and cushioning means which tend to resist the movement of said support under the action of the power of the carriage applied through said feed dogs and irrespective of whether the carriage is feeding under 125 "ordinary" or "reverse" feed.

29. In a typewriting machine, the combination of an escapement wheel, escapement

dogs therefor, pivotally mounted dog carriers, positive connections between said carriers, and dog actuating means adapted to be connected at will to either of said carriers so as to cause the escapement to operate at will either as an ordinary feed escapement or as a reverse feed escapement.

30. In a typewriting machine, the combination of an escapement wheel, escapement dogs therefor, connections adapted to cause said dogs to co-act with the escapement wheel to operate at will either as an ordinary feed or as a reverse feed, final stopping means for said dogs, and intermediate cushioning means therefor.

31. In a typewriting machine, the combination of a power driven carriage; and escapement mechanism therefor comprising an escapement wheel, an anchor escapement device coöperative therewith and having the pallets thereof positively connected by jointed connections to move in unison and by which the movement of one pallet into the path of an oncoming tooth of the escapement wheel will be effected before the other pallet disengages the wheel, and means whereby either pallet may as desired be made the normally engaged pallet and the escapement be made to feed "ordinary" or "reverse" accordingly.

32. In a typewriting machine, the combination of a power driven carriage; and escapement mechanism therefor comprising an escapement wheel, an anchor escapement device coöperative therewith and having the pallets thereof positively connected by jointed connections to move in unison and by which the movement of one pallet into the path of an oncoming tooth of the escapement wheel will be effected before the other pallet disengages the wheel, an actuating device for said anchor escapement device, and means whereby said actuating device may be connected to one or the other of the carriers of said pallets to cause the escapement mechanism to feed "ordinary" or "reverse" as may be desired.

33. In a typewriting machine, the combination of a power driven carriage; and escapement mechanism therefor comprising an escapement wheel, an anchor escapement device coöperative therewith and having the pallets thereof positively connected by jointed connections to move in unison and by which the movement of one pallet into the path of an oncoming tooth of the escapement wheel will be effected before the other pallet disengages the wheel, a movable support on which the parts of said anchor escapement device move in the operation thereof, and cushioning means for resisting the movement of said support under the action of the escapement wheel on the pallets.

34. In a typewriting machine the combination of a power driven carriage; and escapement mechanism therefor comprising an escapement wheel, an anchor escapement device coöperative therewith and having the pallets thereof positively connected by jointed connections to move in unison and by which the movement of one pallet into the path of an oncoming tooth of the escapement wheel will be effected before the other pallet disengages the wheel, means whereby either pallet may as desired be made the normally engaged part and the escapement mechanism be made to feed "ordinary" or "reverse" accordingly, a movable support on which the parts of said anchor escapement device move in the operation thereof, and cushioning means for resisting the movement of said support under the action of the escapement wheel on the pallets.

nation of a power driven carriage; and escapement mechanism therefor comprising an escapement wheel, an anchor escapement device coöperative therewith and having the pallets thereof positively connected by jointed connections to move in unison and by which the movement of one pallet into the path of an oncoming tooth of the escapement wheel will be effected before the other pallet disengages the wheel, means whereby either pallet may as desired be made the normally engaged part and the escapement mechanism be made to feed "ordinary" or "reverse" accordingly, a movable support on which the parts of said anchor escapement device move in the operation thereof, and cushioning means for resisting the movement of said support under the action of the escapement wheel on the pallets and irrespective of whether the escapement mechanism is operating as an "ordinary" or "reverse" escapement.

35. In a typewriting machine, the combination of a power driven carriage; and escapement mechanism therefor comprising an escapement rack, two feed dogs, the engaging portions of which move in the plane of the feed rack into and out of engagement therewith, and means for controlling said feed dogs so that they may be caused to operate indefinitely to afford "reverse" feed or may be caused to operate indefinitely to afford "ordinary" feed as may be desired, said means including means by which either feed dog may be made the normally engaged dog.

36. In a typewriting machine, the combination of a power driven carriage; and escapement mechanism therefor comprising an escapement rack, two feed dogs, both of which always receive movement on their support at each printing operation, and means for controlling said feed dogs so that they may be caused to operate indefinitely to afford "reverse" feed or may be caused to operate indefinitely to afford "ordinary" feed as may be desired, said means including means by which either feed dog may be made the normally engaged dog.

37. In a typewriting machine, the combination of a power driven carriage; and escapement mechanism therefor comprising an escapement rack, two feed dogs both of which always receive movement on their support at each printing operation, one of said dogs in its movement to disengage the rack affording an advance of the carriage whereas the other dog in disengaging the rack moves substantially in the plane of the working face of the engaged tooth of the rack so that no advance of the carriage is afforded during the disengaging movement of said last mentioned dog and while it still engages the rack, and means for controlling said feed dogs so that they may

be caused to operate indefinitely to afford
"reverse" feed or may be caused to operate
indefinitely to afford "ordinary" feed as
may be desired, said means including means
5 by which either feed dog may be made the
normally engaged dog.

Signed at the borough of Manhattan, city

of New York, in the county of New York,
and State of New York, this 28th day of
January, A. D. 1914.
